RAIL ANCHOR

Filed Feb. 18, 1929

By Fisher, Clapp, Isaacs & Pound, Atty's.

UNITED STATES PATENT OFFICE

LOUIS KADAR, OF CHICAGO, ILLINOIS, ASSIGNOR TO CHICAGO RAILWAY EQUIPMENT COMPANY, OF CHICAGO, ILLINOIS, A CORPORATION OF ILLINOIS

RAIL ANCHOR

Application filed February 18, 1929. Serial No. 340,746.

The invention relates to rail anchors or anticreepers and seeks to provide an improved, inexpensive construction comprising a clip adapted to be driven into gripping engagement with one of the rail base flanges, and a separate spring member which is strained when installed on the rail base and which serves to maintain the clip in position upon the rail.

10 The invention consists in the foregoing and other features of improvement herein-after set forth, is illustrated in its preferred form in the accompanying drawing, and is more particularly pointed out in the appended claims.

15 In the drawing:

Figs. 1, 2, and 3 are side, plan, and end views, respectively, of the preferred form of the improved anchor.

20 Fig. 4 is a longitudinal section, and Fig. 5 is a perspective view illustrating modifications of the clip.

The clip which is adapted to grip one of the rail base flanges is preferably formed of 25 a piece of steel plate, say about one-quarter of an inch thick, which is bent to a U-section so that the clip comprises spaced side portions 10 connected by a bent edge portion 11. The side portions of the clip are provided 30 with notches or seats 12 which are adapted to snugly fit the upper and lower faces of one of the flanges of the rail base and so that the clip is adapted to be driven into gripping engagement with one of the rail base 35 flanges, as shown in the drawing, with its side portions 10 substantially vertical and extending above and below the base 13 of the rail. Preferably, the notches or seats 12 are so shaped that the edges thereof do not 40 contact with the edge of the rail base, but do firmly fit and grip the upper and lower faces thereof.

The lower portions of the clip are arranged 45 to engage a part of the sub-structure to prevent creeping of the rail and preferably the side portions of the clip are flared outwardly and downwardly so that the lower tie-abutting portions 14 thereof are spaced vertically some distance below the lower face of the rail base, and are spaced longitudinally in

front and rear of the other parts of the anchor. Thus, these portions engage the tie 15 some distance below its upper face and hold the anchor away from the tie plate 16. Preferably, as shown, the tie-abutting portions 14 are flat and vertical and have rounded edge 55 portions to avoid cutting the tie.

Means for holding the clip in position on the rail base comprises a spring loop 17 which is adapted to extend about the base flange engaged by the clip, and a cross-arm 18 having an offset 19 at its end which is arranged to engage the other base flange. Preferably, as shown the spring loop 17 and cross-arm 18 are integrally formed of spring steel of round 60 section which may be about five-eighths of an inch or more in diameter.

The spring loop is provided with a down-turned end portion 20 which is arranged to bear upon the upper face of the rail base and 65 also engage an abutment in the form of a spacing rivet 21 which extends between the side portions 10 of the clip. The loop also extends loosely through openings 22 in the outer bent edge portion 11 of the clip and which 70 openings, when the anchor is in position on the rail, are disposed above and below the level of the rail base. The cross-arm 18 extends upwardly at an incline from the lower 75 end of the spring loop and, as stated, it is 80 provided at its end with an offset 19 which is arranged to bear against the edge of the opposite base flange. Preferably, as shown, the offset 19 is provided with a lip 23, which, 85 when the anchor is in position on the rail, slightly overlaps the edge of the base flange.

In applying the anchor to the rail, both the clip and spring member are applied from one side of the rail and forced as far as possible by hand on one of the rail base flanges, 90 in which condition, the offset end 19 of the spring member engages the lower face of the rail base. The outer portion of the spring loop 17 is then struck a sharp blow or blows 95 with a hammer or like instrument until the clip and spring member are forced far enough on to the rail base to permit the offset end 19 of the member to clear and snap into engagement with the edge of the opposite base flange, as shown in full line in Fig. 100

ure 1. When the spring member is thus struck, the engagement of its upper end portion with the abutment or rivet 21 of course also forces the clip into gripping engagement with the rail base flange. The manufactured shape of the spring member is indicated in dot and dash lines in Fig. 1 and is such that, when the anchor is installed on the rail base, the spring member is strained or distorted, the end portions 19 and 20 being spread apart both vertically and horizontally. Thus, when the anchor is driven to position far enough to permit the offset end 19 to clear the rail base, it will snap into the position shown in full lines in Fig. 1.

Also, when in position on the rail base, the engagement of the ends 19 and 20 of the spring member with one edge of the rail base and with the abutment 21 respectively, serves to laterally compress the spring loop 17. Because of the stresses thus developed in the spring member, the hooked end 19 of the cross-arm is forced both vertically and horizontally into engagement with the adjacent rail base flange and the end portion 20 is firmly pressed against the abutment or rivet 21 and so serves to prevent the loosening of the grip of the flange-engaging clip.

The improved anchor is relatively light in weight and inexpensive to manufacture; it can be readily applied to the rail and in its preferred form shown is adapted to cooperate with the sub-structure of the track to prevent creeping of the rail in either direction. The abutment or rivet 21 and openings 22 of the clip and the loop 17 of the spring member are so related that the spring member and clip are permanently connected; that is to say, they cannot be disengaged without removing the rivet when the anchor is not in position upon the rail.

The clip and spring member of the anchor are assembled at the factory and shipped as a unit. The parts are assembled by passing the loop of the spring member through the slots 22 of the clip, and then the sides 10 of the clip are connected by the rivet 21, which, as stated, is so located as to limit the movement of the spring member and to prevent its disengagement from the clip.

In the modified form of the clip shown in Fig. 4, the bent connecting portion 11' between the sides 10 of the clip is at its inner edges and the upper part of this connecting portion forms the abutment for the end 20 of the spring loop 17, while its lower part is provided with an opening 24 through which the cross-arm 18 loosely extends. In other respects, this modified form of clip is preferably similar to that shown in Figs. 1, 2 and 3. Shouldered spacing rivets 25 connect the side portions 10 of this clip and are disposed above and below the flange-receiving notches or seats 12'. One of these rivets is located adjacent and within the upper portion of

the loop 17 and the other adjacent and above the end of the cross-arm 18 and they serve to connect the clip and spring member when the anchor is not in use.

In the form shown in Fig. 5, the bent portion 11' of the clip is at its upper edge and the lower portions of the side members 10' are bent outwardly and downwardly to form tie-engaging abutments 14'. The spring member is similar to that already described and is preferably interlocked with the clip by the abutment or rivet 21' and additional spacing rivets 26.

Changes may be made in the preferred details set forth without departure from the scope of the appended claims.

I claim as my invention:

1. A rail anchor comprising a clip for gripping one of the rail base flanges, a spring loop adapted to extend about the same base flange and be compressed on installation to hold the clip in position, and a retaining bar for the spring loop adapted to engage the opposite base flange.

2. A rail anchor comprising a clip for gripping one of the rail base flanges, a compressible spring loop adapted to extend about the same base flange and having an inwardly extending upper end arranged to engage and resiliently maintain the clip in position, and retaining means adapted to engage the edge of the opposite flange and hold the spring loop compressed.

3. A rail anchor comprising a clip adapted to be driven into gripping engagement with one of the rail base flanges, a compressible spring loop adapted to extend about the same base flange and having a downturned end portion arranged to bear upon the upper face of the flange and engage said clip, and retaining means arranged to engage the other base flange and hold the spring loop compressed.

4. A rail anchor comprising a clip for gripping one of the rail base flanges, and a compressible spring loop adapted to extend about the same base flange with its upper, inwardly and downwardly extending end portion engaging said clip, the lower portion of said loop terminating in a cross bar and the latter having an offset adapted on installation to snap into engagement with the opposite base flange.

5. A rail anchor comprising a clip for gripping one of the rail base flanges, a substantially C-shaped spring loop adapted to encircle the same base flange in spaced relation thereto and having a downturned upper end portion arranged to bear upon the upper face of the flange and abut against a part of said clip to resiliently hold the same in position, the lower portion of said spring loop terminating in an integral upwardly inclined cross-bar, and the latter having a hooked end, adapted, on installation of the anchor,

to snap into engagement with the edge of the other base flange.

6. A rail anchor comprising a spring loop having end portions adapted, on installation, to be spread apart vertically, and a clip adapted to be held in gripping engagement with one of the rail base flanges by said spring member, the anchor having means arranged to engage the edge of the other base flange and cooperate with said clip to compress said loop in horizontal direction.

7. A rail anchor comprising a clip and a spring loop adapted to be driven onto one of the rail base flanges, with the clip gripping such flange and a downturned upper end portion of the loop bearing upon the upper face thereof and engaging said clip, the lower portion of said loop terminating in an integral cross-bar, and the latter having an offset adapted to snap into engagement with the edge of the other base flange.

8. A rail anchor comprising a clip and a spring loop adapted to be driven onto one of the rail base flanges with the clip gripping such flange, said loop having downwardly and upwardly faced end portions arranged to be spread apart on installation both vertically and transversely of the rail and bear upon the upper face of said flange and the lower face of the rail base respectively, and means engaging the edge of the other base flange and cooperating with said loop to resiliently hold said clip in position.

9. A rail anchor comprising a clip for engaging one of the rail base flanges, and a separate spring member permanently connected to said clip and adapted to snap into engagement with the edge of the other base flange for holding the same in position on the rail.

10. A rail anchor comprising a clip of U-section for gripping one of the rail base flanges with its side portions substantially vertical, and retaining means for the clip comprising a spring loop disposed between the side portions of the clip and permanently connected thereto, and a part connected to said spring loop and having means for engaging the other base flange.

11. A rail anchor comprising a clip of U-section for gripping one of the rail base flanges with its side portions substantially vertical, and a retaining spring member having a loop at one end arranged between the side portions of said clip and connected thereto and adapted to encircle and bear upon the upper face of the adjacent base flange, said spring member having means at its opposite end for engaging the other base flange.

12. A rail anchor comprising a clip of U-section for gripping one of the rail base flanges with its side portions substantially vertical and its bent connecting portion at its outer edge, and a retaining spring member having an upwardly projecting loop at

one end disposed between the side portions of the clip and extending through openings in the outer bent portion thereof, said loop having a downturned end arranged to bear upon the upper face of the adjacent flange and the clip having an abutment extending between its side portions and engaged by said loop end, and said spring member having an offset at its opposite end arranged to snap into engagement with the edge of the other base flange.

13. A rail anchor comprising a clip adapted to be driven into gripping engagement with one flange of the rail base, and a retaining spring member arranged to engage the clip and hook over the edge of the other base flange, said clip having a downwardly and forwardly projecting portion spaced below the rail base and arranged to hold the other part of the anchor spaced from the adjacent cross tie.

14. A rail anchor comprising a clip adapted to be driven into gripping engagement with one flange of the rail base, and a retaining spring member arranged to engage the clip and the edge of the other base flange, said clip having a U-section with spaced substantially vertical sides the lower portions of which are spaced below the rail base and are offset forwardly and rearwardly respectively of the other parts of the anchor to form tie-engaging abutments.

15. A rail anchor comprising a clip of U-section for gripping one of the rail base flanges with its side portions substantially vertical, a retaining spring member having an offset at one end for engaging the other base flange and a loop at its opposite end disposed between the side portions of said clip, arranged to extend about the adjacent rail flange and having a downturned end portion arranged to bear upon the upper face of such flange, and said clip having an abutment between its side portions against which the end of said loop abuts.

16. A rail anchor comprising a clip arranged to grip one of the rail base flanges and extend below the same to engage a part of the sub-structure, and a retaining spring member adapted to be strained on installation and having end portions arranged to extend about the edges of and bear upon the opposite rail base flanges with one end portion engaging said clip.
